UNITED STATES PATENT OFFICE.

LESLIE W. CLAYBURN, OF MILWAUKEE, WISCONSIN.

INKING MECHANISM FOR PRINTING MACHINERY.

Application filed October 21, 1925. Serial No. 63,973.

My invention relates to inking mechanism for printing machinery, and is exemplified as employed in connection with a rotary form cylinder. The term form cylinder includes any cylinder having thereon printing letters, lines or configurations, whether on the cylinder itself, or on type, cuts or plates attached to the cylinder.

It is the object of my invention to provide new and improved means whereby even distribution of the ink is obtained, so as to effect a uniform and even application of ink to the printing surfaces; further, to provide novel means for adjusting the form rollers with relation to the printing form; further, to provide novel means whereby the form rollers are simultaneously moved out of contact with the printing form while the ink distributing contact of said form rollers is maintained; further, to provide novel means for adjusting the form rollers with relation to a coacting inking roller; further, to provide means for moving the form rollers in directions toward and from the printing form and in directions toward and from their ink supplying rollers in sequence; further, to provide novel means whereby the form rollers are adjusted toward and from the printing form to compensate for variations in diameters of the form rollers during operation; further, to provide novel means whereby a composition roller is adjusted toward and from a coacting inking roller; further, to provide novel means whereby a composition roller is adjusted laterally about an inking roller for adjusting contact relation with a neighboring part; further, to provide novel means for adjusting the contact relations between distributing rollers and a reciprocating roller coacting therewith whereby the pressures of contact between the same are adjusted; further, to provide novel means whereby the form rollers and the distributing rollers are connected for combined movements; and, further, to provide means whereby the form rollers are released from contact with the printing form, and the distributing rollers and form rollers have contact with their respective reciprocating rollers, for distributing ink over the cylindrical surfaces of all of the rollers without transference of the same to the form cylinder.

It is the object of my invention further, to provide novel means whereby all the

printing rollers are freed from contact with each other and with the printing form, and preferably spaced apart, for ready access to all parts of the printing rollers and for ready turning of the same out of contact whereby to readily clean all the inking surfaces thereof; and, further, to position all the composition rollers out of contact when not in use in order to maintain their cylindrical shapes.

The invention will be further readily understood from the following description and claims, and from the drawings, in which latter:

Fig. 1 represents an end elevation of my improved device, viewed from the gear side of the printing press.

Fig. 2 is an end elevation of the same, viewed from the feed side of the printing press, and partly in section on the irregular line 2—2 of Fig. 4.

Fig. 3 is a vertical cross-section of the same, taken in the plane of the line 3—3 of Fig. 4, partly broken away.

Fig. 4 is a horizontal section, showing one end of my improved device, partly broken away, and taken on the line 4—4 of Fig. 2, and showing the feed side of the printing press.

Fig. 5 is a horizontal section of the same, partly broken away, taken in the plane of the line 5—5 of Fig. 8.

Fig. 6 is a vertical section, partly broken away, taken in the plane of the irregular line 6—6 of Fig. 8.

Fig. 7 is a vertical axial section of the same, taken on the irregular line 7—7 of Fig. 2.

Fig. 8 is a vertical cross-section of my improved device, partly broken away, and taken in the plane of the line 8—8 of Fig. 9.

Fig. 9 is a horizontal section, showing part of the gear train, and taken on irregular line 9—9 of Fig. 8.

Fig. 10 is a vertical section of a detail showing the adjustment at one end of the feed roller, and taken on the line 10—10 of Fig. 2.

Fig. 11 is a vertical section, taken in the plane of the irregular line 11—11 of Fig. 13, showing the adjustments for the distributing rolls.

Fig. 12 is a detail of the same, shown in cross-section in the plane of the line 12—12 of Fig. 13.

Fig. 13 is an axial section of the same, partly broken away, taken in the plane of the irregular line 13—13 of Fig. 11.

Fig. 14 is a detail of the same, taken in the plane of the line 14—14 of Fig. 13.

Fig. 15 is a detail of an adjustment for the form rollers, taken in the plane of the line 15—15 of Fig. 7.

Fig. 16 is a vertical section, showing the means for adjusting the form rollers, taken in the plane of the line 16—16 of Fig. 7.

Fig. 17 is a detail of the same, taken in the plane of the line 17—17 of Fig. 16.

Fig. 18 is a detail of the same, taken in the plane of the line 18—18 of Fig. 17.

Fig. 19 is an end elevation, partly in section, showing the lowermost form roller and its mounting, with the roller in contact with the form cylinder and its reciprocating roller.

Fig. 20 is a similar view of the same, showing the form roller moved out of contact.

Fig. 21 is an end elevation, partly in section, showing the lower intermediate form roller and its mounting, with the roller in contact with the form cylinder and its co-acting reciprocating roller.

Fig. 22 is a similar view of the same, with the form roller moved out of contact.

Fig. 23 is an end view, partly in section, showing the uppermost form roller and its mounting, with the roller in contact with the form cylinder and its reciprocating roller.

Fig. 24 is a similar view of the same, with the form roller moved out of contact.

Fig. 25 is an end elevation of the upper intermediate form roller and its mounting, with the roller in contact with the form cylinder and its reciprocating roller.

Fig. 26 is a similar view of the same, with the form roller moved out of contact.

For convenient reference it may be stated that Figs. 1, 5, 6 and 9 are views taken at the gear side of the printing press; that Fig. 8 is a view of the gear side of the printing press looking from the feed side of the printing press; and that Figs. 2, 3, 4, 7 and 10 to 26 inclusive are views of the feed side of the printing press or taken in directions viewed from the feed side of the printing press.

It may be further stated that a great many of the parts at the feed side of the printing press are duplicated at the gear side of the printing press. The following description of the present exemplification will be made primarily from the feed side of the printing press, and where similar parts are located at the gear side of the printing press, such similar parts will be designated by similar but primed reference numerals.

The frame of the machine is represented

at 31, at the respective sides of which there are bearing spiders 32, 32', respectively secured to the frame by tie bolts 33, 33'. (See Figs. 1, 2, 4, 5, 6 and 7.)

A usual ink fountain 35 is mounted on the frame, and comprises a fountain roller 36, suitably rotated from an operating part of the printing press, and a usual adjusting blade 37, adjustable at various points along its length with relation to the fountain roller, by screws 38 in usual manner, for adjusting the thickness of the film of ink carried by the latter. (See Figs. 1 and 3.)

A feed roller 41 is mounted in the frame, as in bearings 42, 43, at its respective ends. (See Figs. 3, 9 and 10.) The bearing 43 is on a bracket 44 fixed to the frame. The feed roller is adjustable for parallelism between it and the fountain roller, as by mounting its bearing 42 on the slide 45, adjustable laterally on a guideway 46 fixed to the frame. A bolt 47 is threaded into the slide, and is received through registering holes 48 in the guideway, the frame and an outer guide plate 49, the latter being fixed to the frame by a bolt 50.

The bolt 47 is also received through a hole 51 in a slide 52 which has a threaded bearing 53 in which a bolt 54 is received, the latter being journaled in bearing lugs 55, on the guide plate 49, and held in endwise relation in said bearings between the head of said bolt at one end and a collar 56 fixed to said bolt at its other end.

Rotation of the bolt 54 causes movement of the slide 52, and consequently of the bearing 42, lengthwise of the bolt, in one direction or the other according to the direction of rotation of said bolt 54. When the adjustment has been made, the parts are clamped together by drawing up the bolt 47. (See Figs. 2 and 10.)

A ductor roll 61 is movable laterally between the fountain roller and the feed roller for transferring sections of the film of ink from the fountain roller to the feed roller. The section of film thus transferred at each oscillation of the ductor roller extends over a considerable portion of the periphery of the ductor roller, so as to convey a film of ink to the feed roller rather than a strip of ink. The shaft of the ductor roller is suitably mounted, as on arms 62, at its respective ends, adjustably fixed to a rock-shaft 63, in usual manner. The rock-shaft is suitably journaled in bearings in the frame, and has an operating arm 64 fixed thereto, operated for instance by a link 65, having articulating connection 66, with said arm, the link being operated from a suitable part of the press. (See Figs. 1 and 3.)

A reciprocating roller 71 is provided with axles 72, 72', at its respective ends, the axles being journaled in sleeves 73, 73', fixed to the frame. (See Figs. 4 and 5.)

A pair of sets of distributing rollers 74, 75, 76, and 77, 78 and 79, are arranged respectively above and below the reciprocating roller. The distributing rollers are respectively provided with axles 81 and 81' at their respective ends, journaled in bearings 82 and 82' at the respective sides of the press. Each of the bearings comprises a releasable cap 83, for ready removal of the roller, the cap being pivoted on a pintle 84, and clamped in place by a bolt 85 threaded in the base of the cap. (See Fig. 11.) Each of these distributing rollers makes contact with the reciprocating roller 71 for mutually distributing ink over the same. The distributing rollers 74, 77, also normally make contact with the feed roller 41 for receiving the film of ink from the latter and conveying it to the reciprocating roller. (See Figs. 1, 2, 3 and 11.)

The reciprocating roller 71 is exemplified as a roller having a large diameter. A pair of reciprocating rollers 87, 88, respectively coact with the end ones of the respective sets of distributing rollers.

These reciprocating rollers are respectively provided with axles 89, 89', 90, 90', at their respective ends, which axles respectively rotate in sleeves 91, 91', 92, 92', respectively fixed to the frame of the machine. (See Figs. 1, 2, 6, 7 and 8.)

Endwise reciprocation is imparted to the reciprocating rollers 71, 87, 88, as by providing the axle 72 with a spool 93 fixed thereto, and providing the respective axles 89, 90, with spools 94, 95, fixed thereto respectively.

A rocker frame 96 is provided with bearings 97 rockable on a stub shaft 98 in a bearing 99 extending from the spider 32. (See Figs. 2, 4 and 7.) The rockable frame is provided with arms 101, 102, 103, respectively provided with rollers 104, 105, 106, received in the annular grooves of the spools 93, 94, 95. The rocker-frame is arranged to be rocked on said stub shaft, as by providing it with an arm 107, which has an articulation 108 with a link 109, suitably operated by an operating part of the press, for imparting reciprocating motions to the rocker-frame. The arms on the rocker-frame are arranged to reciprocate the reciprocating rollers 71, and 87, 88, in opposite directions. The axles of said reciprocating rollers rotate and move axially in their respective sleeves.

The distributing rollers 76, 79, of the respective sets of distributing rollers, coact with the respective reciprocating rollers 87, 88, for conveying the distributed ink from the respective distributing rollers to said respective reciprocating rollers 87, 88, which are in spaced apart relation, for respectively serving a pair of form rollers 111, 112, and a pair of form rollers 113, 114. These pairs of form rollers are the end rollers of the

respective sets of rollers, which are served from the respective sides of the feed roller.

The form rollers are arranged to ink the printing surface on the printing form, which is exemplified as, a form cylinder 70 115, and shown as a plate cylinder, having curved printing plates 116 suitably secured thereto in well-known manner.

The form cylinder is suitably mounted and rotated in the frame, the means for 75 mounting and rotating the same not being more particularly shown or described, because any well known means for accomplishing the purpose may be employed.

It will thus be seen that the ink received 80 in a film from the fountain roller, is conveyed to a feed roller and from the latter to opposite sets of distributing rollers, between which a reciprocating roller rotates and reciprocates, the distributed ink being 85 conveyed to spaced apart smaller reciprocating rollers, which respectively serve separate pairs of form rollers, as will be noticed from Fig. 3. A system of rollers is thus provided which has a maximum number of 90 contacts with each other within a small compass, there being twelve points of reciprocating contact between the three reciprocating rollers and the distributing 95 rollers and form rollers respectively, making twelve points of reciprocating contact between thirteen rollers for effective and even distribution of the ink when it reaches the printing surface on the form cylinder.

The ductor roller, the distributing rollers 100 and the form rollers, are in practice made of suitable metal tubes surrounded by suitable composition for the rollers, the rest of the rollers being preferably metal rollers.

Means are also provided for moving all 105 of the distributing rollers toward and from the reciprocating roller between the same and toward and from the other rollers co-operating therewith. (See Figs. 4, 5, 11, 12, 13 and 14.) Thus the rollers 74, 75, 76, are 110 mounted in adjustable relation at their respective ends on supporting plates 121, 121' at the respective sides of the frame of the press, and the distributing rollers 77, 78, 79, are mounted in adjustable relation at their 115 respective ends on supporting plates 122, 122'. The supporting plates 121, 122, are provided respectively with guideways 123, 124, in which guides 125, 126, extending from the frame, are received, for guiding 120 said supporting plates.

The supporting plate 121 is provided with a loop 128, and the supporting plate 122 is provided with a loop 129.

A cam sleeve 131 is received about the sleeve 73 fixed to the frame, and has thereon cams 132, 133. The supporting plate 121 and its loop has guides 134, 135, secured thereto at the respective sides of said cam sleeve. The supporting plate 122 and its 130

loop has guides 136, 137, secured thereto at the respective sides of the cam sleeve.

Cam shoes 138, 139, are received between the cam 132 and the respective guides 134, 135, and cam shoes 140, 141, are received between the cam 133 and the respective guides 136, 137. The cams, and the shoes and guides co-operating therewith, are so arranged, that when the cam sleeve is rotated, the supporting plates with the distributing rollers supported thereby, are moved either toward the reciprocating roller 71 or away from said reciprocating roller at both ends by mechanism to be presently described.

Thus a shaft 130 is journaled in a bearing 142 in the bearing spider 32 at the feed side of the press, and is provided with a pinion 143 which meshes with a segment gear 144 on the cam sleeve. (See Figs. 2 and 4.)

This shaft is provided with a hand-wheel 145 for operating the same. This shaft also carries a pinion 146, which meshes with a pinion 147, on a stub shaft 148, fixed in the bearing spider 32. The pinion 147 meshes with a segment gear 149, fixed to a shaft 150, journaled in a sleeve 151, and in bearings 152 and 152' in the spiders 32 and 32'. The sleeve is journaled in bearings 153, 153', in the frame, at the respective sides of the press. (See Figs. 4 and 5.)

A segment gear 149' is fixed to the other end of said shaft and meshes with a pinion 147' on a stub shaft 148' fixed to the bearing spider 32'. This pinion meshes with a pinion 146' on a stub shaft 130' in a bearing 142' in said bearing spider 32', the last-named pinion being elongated and also meshing with a segment gear 144' on the cam sleeve 131' at the other side of the printing press.

Means are further provided for imparting lateral adjustments to the distributing rollers in directions about the outer periphery of the reciprocating roller 71, these adjustments being of the distributing rollers 74 and 75, and 77 and 78, toward and from the feed roller, and of the distributing rollers 76 and 79 toward and from the respective reciprocating rollers 87, 88, and means are further provided for adjusting the distributing rollers toward and from the axis of the reciprocating roller with which they coact.

Thus the supporting plate 121 is provided with an arcuate slot 155, in which an arcuate rib 156 on a slide 157 is received. (See Figs. 11 and 13.) A bolt 158 is journaled in a bushing 159 in a bearing 160 on the supporting plate 121. It has a nut 161 fixed thereto outside said bushing. The bolt is received through a cam slot 162 in the slide 157, and has threaded connection with a cam block 163 in said cam slot. The outer end of the bolt has a washer 164 across the outer end of said cam slot, a clamp nut 165 being

threaded to said bolt and arranged to clamp said washer, said slide, said supporting plate and said bushing between said nut and the end limit nut 161.

The cam slot is at an angle to the plane of the slide 157, so that the slide will be moved laterally on its arcuate guide by axial movement of the cam block by means of the bolt, whereby the distributing roller 76, mounted on said slide, is moved laterally toward or away from the reciprocating roller 87. (See Figs. 3, 11, 12, 13 and 14.)

Similar means designated by similar reference numerals are employed to laterally adjust a slide 167, which supports the distributing roller 79, and similar means designated by similar reference numerals, are employed to adjust slides 168, 169, along the arcuate guides 155, the distributing rollers 74, 75, and 77, 78, being mounted on said respective slides 168, 169. (See Figs. 11, 12, 13 and 14.)

The means for adjusting the distributing rollers toward and from the reciprocating roller are similar for each of said distributing rollers, a description of one sufficing for all. The slides 157, 167, 168, 169 are provided with guideways 171, on each of which a slide 172 is adjustable, the slide carrying the bearing for the distributing roller. (See Figs. 11 and 13.)

Each of these bearings is provided with a fork 173, the tines of which are received at the respective sides of the outer portion of the slide on which it is mounted. Each of these tines is provided with a bearing 174, in which a bushing 175, is received, a bolt 176 being journaled in said bushings and having a nut 177 fixed thereto at one end and a head at its other end, endwise movement of said bolt being prevented by said nut and head. A cam block 178 has threaded connection with said bolt and coacts with the walls of the cam slot 179 in the outer end of the slide. This cam slot slants in the plane of the guideway 171 in a direction transverse to the plane of the fork.

The adjustment of this cam block adjusts the bearing block carried by the fork laterally, for adjusting the end of the distributing roller laterally, each end of the distributing roller being separately adjustable by similar means, in order that parallelism between the cooperating contact portions of the distributing rollers and the reciprocating roller may be obtained.

After these adjustments are made the parts are clamped in adjusted positions at the respective sides of the press by clamping means exemplified as comprising, at the feed side, a washer 181 received about the cam sleeve 131 inside the segment gear 144, the latter forming a shoulder bearing on the clamping washer. (See Figs. 4, 5 and 13.) The clamping washer in turn bears upon the slides 157, 167, 168 and 169. The latter

bear upon the supporting plates 121 and 122, and the latter bear upon the frame.

The outer end of the sleeve 73 is threaded and has a nut 182 received thereover. The 5 nut has an operating handle 183 thereon. (See Figs. 1, 4, 5 and 13.)

The cam sleeve 131 has an extension 184 which extends through a bearing 185 of the bearing spider 32. The nut 182 bears on the 10 end of the extension and forces the cam sleeve inwardly, whereby the shoulder thereon, formed by the segment gear 144 bears upon the clamping washer 181 and clamps the slides and the supporting plate toward 15 the frame, for maintaining the parts in adjusted positions.

The form rollers are provided with axles 191, 191', at their respective ends, the axles 191 being journaled in bearings 192, 193, 20 194, 195.

Means are provided for adjusting each of the form rollers independently at each end, toward and from the reciprocating roller coacting therewith, and means are provided 25 for adjusting each end of each of the form rollers laterally about the reciprocating roller coacting therewith, toward and from the printing form. These reciprocating rollers are located between the form rollers 30 of each pair of form rollers, as hereinbefore described.

Each of the bearings for the form rollers is provided with a cap 196, which is readily movable for removing the roller, these caps 35 being hinged on pintles 197 and clamped in positions by bolts 198 threaded to the base of the bearing. (See Fig. 16.)

The bearings for the respective form 40 rollers are mounted on slides 201, 202, 203 and 204, respectively slideable on guideways 205, 206, 207, 208, on arms 209, 210, 211, 212. (See Figs. 16 and 19 to 26 inclusive.)

The guideway 208 for the lowermost form 45 roller is mounted on the arm 212. (See Figs. 1, 2 and 16 to 26 inclusive.) The bearing 195 is provided with a fork shown at 213, the tines of which are provided with holes 214, in which bushings 215 are located. (See particularly Figs. 16, 17 and 18.) A 50 bolt 216 is received through said bushings and is threaded to a cam block 217, slideable in a cam groove 218 in the arm 212. The bolt is provided with a nut 219 fixed thereto, the bolt being held in endwise relation by 55 the head of the bolt and said nut, so that rotation of the bolt will cause axial movement of the cam block 217 in the cam slot, for moving the bearing on the guideway, for lateral adjustment of one end of the form 60 roller therein.

There are similar parts at the other end of the roller, designated by similar but primed reference numerals, for moving the other end of the roller in similar manner.

65 The bearing 194 for the intermediate

lower form roller is on the slide 203, which is adjustable laterally on the guideway 207 on the arm 211. (See Figs. 21 and 22.) The bearing 194 is provided with a fork 220 similar to the fork shown at 213, and is 70 adjustable on the guideway 207, by a bolt and cam block and connections therefor, similar to the bolt 216 and the cam block 217 and connections therefor, described with reference to the lowermost form roller 114, 75 (see Figs. 17, 18, 19 and 20). The parts are designated by similar reference numerals.

There are similar parts at the other end of the intermediate lower form roller, designated 80 by similar but primed reference numerals.

The bearing 192 for the axle of the uppermost form roller is at one end mounted on the slide 201, which has thereon a fork 221 85 similar to the fork 213, and is adjustable on the guideway 205 by a bolt and cam block and connections therefor, similar to the bolt 216 and the cam block 217 described with reference to the lowermost form roller, these 90 parts are designated by similar reference numerals. (See Figs. 16 to 20, 23 and 24.)

The bearing 193 for the intermediate upper form roller is on the slide 202 which is 95 adjustable laterally on the guideway 206 of the arm 210. (See Figs. 25 and 26.) This slide is provided with a fork 222 similar to the fork 213 and is adjustable on the guideway 206 by a bolt and cam block and connections therefor, similar to the bolt 216 and the cam block 217 described with reference to the upper form roller. These parts are 100 designated by similar reference numerals.

The adjustments just described of the 105 bearings of the various form rollers at their respective ends on their guideways, are for the purpose of adjusting the form rollers laterally with relation to the reciprocating rollers 87, 88, in order to obtain proper ink 110 transferring contact between reciprocating rollers and said form rollers throughout their lengths.

Means are also provided for adjusting said 115 form rollers toward and from the printing form, in order to obtain proper ink transferring contact between each of the form rollers, throughout its length, with the printing lines on the printing form. In order that such adjustment with relation to the printing form may not affect the adjustment or 120 relation of the form rollers with the reciprocating rollers with which they respectively coact, such adjustments are made about the axes of said respective reciprocating rollers. These adjustments will now be described.

125 The arm 212 for the lowermost form roller has a bearing 225 about a journal stub 226 on an arm 227. The axis of this bearing is substantially coincident with the axis of the reciprocating roller 88 with which the form 130

roller thereon coacts, when said form roller is in operative position. The arm 227 is provided with a bearing 228 in which there is a bushing 229 which has a bolt 230 therethrough. (See Figs. 6, 7, and 16 17, 19 and 20.) The arm 212 is provided with a cam groove 231 in which a cam block 232 is slidable. This cam groove slants toward and from the form roller which it adjusts, and 10 at substantial right angles to the inclination of the cam groove 218.

The cam block has threaded connection with the bolt 230. The bolt has a nut 233 fixed thereto, there being a washer 234 between said nut and the arm 212 across the end of the opening of the cam groove. The bolt is held endwise between its head and said nut. Rotation of the bolt in one direction or the other moves the cam block axially 20 thereon and the coacting cam surfaces between said cam block and the walls of said cam groove cause the arm 212 to be rocked on the stub 226, whereby the bearing 195 is caused to move laterally in one direction or 25 the other, substantially about the axis of the reciprocating roller coacting therewith, for adjusting an end of the form roller 114 toward and from the form cylinder.

The means for adjusting the arm 212' at 30 the other end of the lowermost form roller comprises similar parts designated by similar but primed reference numerals. (See Fig. 6.)

The arm 211 for the intermediate lower form roller has a bearing 235 about a journal stub 236 on an arm 237. The axis of this bearing is substantially coincident with the axis of the reciprocating roller 88 with which the form roller thereon coacts, when said 35 form roller is in operative position. The arm 237 is provided with a bearing 238 in which there is a bushing 239 which has a bolt 240 therethrough. (See Figs. 6, 7, 16, 21 and 22.) The arm 211 is provided with a cam groove 241 in which a cam block 242 is slidable. This cam groove and this cam block are similar in construction and operation to the cam groove 231 and the cam block 232. (See Fig. 17.)

This cam block has threaded connection with the bolt 240. The bolt has a nut 243 fixed thereto, there being a washer 244 between said nut and the arm 211 across the end of the opening of the cam groove. The bolt is held endwise between its head and said nut. Rotation of the bolt in one direction or the other moves the cam block axially 45 thereon and the coacting cam surfaces between said cam block and the walls of said cam groove cause the arm 211 to be rocked on the stub 236, whereby the bearing 194 is caused to move laterally in one direction or the other, substantially about the axis of the reciprocating roller coacting therewith, for adjusting an end of the form 50

roller 113 toward and from the form cylinder.

The means for adjusting the arm 211' at the other end of the intermediate lower form roller comprises similar parts designated by similar but primed reference numerals. (See Fig. 6.)

The arm 209 for the uppermost form roller has a bearing 245 about a journal stub 246 on an arm 247. The axis of this bearing is substantially coincident with the axis of the reciprocating roller 87 with which the form roller thereon coacts, when said form roller is in operative position. The arm 247 is provided with a bearing 248 in which there is a bushing 249 which has a bolt 250 therethrough. (See Figs. 6, 7, 16, 23 and 24.) The arm 209 is provided with a cam groove 251 in which a cam block 252 is slidable. This cam groove and this cam block are similar in construction and operation to the cam groove 231 and the cam block 232. (See Fig. 17.)

This cam block has threaded connection with the bolt 250. The bolt has a nut 253 fixed thereto, there being a washer 254 between said nut and the arm 209 across the end of the opening of the cam groove. The bolt is held endwise between its head and said nut. Rotation of the bolt in one direction or the other moves the cam block axially thereon and the coacting cam surfaces between said cam block and the walls of said cam groove cause the arm 209 to be rocked on the stub 246, whereby the bearing 192 is caused to move laterally in one direction or the other, substantially about the axis of the reciprocating roller coacting therewith, for adjusting an end of the form roller 114 toward and from the form cylinder.

The means for adjusting the arm 209' at the other end of the uppermost form roller comprises similar parts designated by similar but primed reference numerals. (See Fig. 6.)

The arm 210 for the intermediate upper form roller has a bearing 255 about a journal stub 256 on an arm 257. The axis of this bearing is substantially coincident with the axis of the reciprocating roller 87 with which the form roller thereon coacts when said form roller is in operative position. The arm 257 is provided with a bearing 258 in which there is a bushing 259 which has a bolt 260 therethrough. (See Figs. 6, 7, 16, 25 and 26.) The arm 210 is provided with a cam groove 261 in which a cam block 262 is slidable. This cam groove and this cam block are similar in construction and operation to the cam groove 231 and the cam block 232. (See Fig. 17.)

This cam block has threaded connection with the bolt 260. The bolt has a nut 263 fixed thereto, there being a washer 264 be-

tween said nut and the arm 210 across the end of the opening of the cam groove. The bolt is held endwise between its head and said nut. Rotation of the bolt in one direction or the other moves the cam block axially thereon and the coacting cam surfaces between said cam block and the walls of said cam groove cause the arm 210 to be rocked on the stub bearing 256, whereby the bearing 193 is caused to move laterally in one direction or the other, substantially about the axis of the reciprocating roller coacting therewith, for adjusting an end of the form roller 112 toward and from the form cylinder.

The means for adjusting the arm 210 at the other end of the intermediate upper form roller comprises similar parts designated by similar but primed reference numerals. (See Fig. 6.)

Means are further provided for simultaneously moving the form rollers in directions toward and from the form cylinder, and means are also provided for simultaneously moving the form rollers toward and from the reciprocating rollers with which they respectively coact. These means are preferably so arranged that these movements may be independent and preferably sequential, in such manner that the form rollers may be, firstly, moved away from the form cylinder, while their ink transferring contacts are maintained with the reciprocating rollers, and, secondly, so that the form rollers may be moved away from their respective reciprocating rollers. The movements in reverse directions are in reverse sequence.

The objects of these respective movements are, firstly, that the form rollers may be moved away from the form cylinder, in order that proper and even ink distribution on the rollers may be effected, for instance, in inking up the press, while the form rollers are out of contact with the form cylinder, and so that, secondly, the form rollers may be moved out of contact with the reciprocating rollers as well as with the form cylinder, in order that the form rollers and the reciprocating rollers may be readily cleaned, and, so that the form rollers, which are composition rollers, may, when the press is idle, be moved so that their surfaces are free of contact, in order that the cylindrical forms of their outer peripheries may not be disturbed, as by the formations of flat spots or impressions therein.

The means for effecting these movements are instanced as comprising eccentrics or cams fixed to rotate with a cam sleeve 151, which extends across the press, and by providing each of the arms, on which the respective form rollers are mounted, with a pair of cam slots, with which a pair of the cams on the cam sleeve coact, the pairs of

cams and cam slots being so arranged that the desired movements of the arms for the described movements of the form rollers may be effected. (See Fig. 4.)

Thus the arm 227 is provided with a guideway 271 in which a guide block 272 is received, the guide block being rockable on the flanged sleeve 92. (See Figs. 6, 7, 16, 19 and 20.) The inner end of said arm is provided with two cam slots 273, 274, in which cams 275, 276, fixed to rotate with the cam sleeve 151, are rotatable. This cam sleeve extends across the machine so as to connect the cams at the respective sides of the printing press, in order to simultaneously move both ends of the form roller 114. It will be noted from Figs. 19 and 20 that said cam slots are arranged in crossing relation, and that the cams are arranged in substantial oppositely extending relation for obtaining the desired sequential movements of the arm 227.

The arm 237 is provided with a guideway 281 in which a guide block 282 is received, the guide block being rockable on the flanged sleeve 92. (See Figs. 6, 7, 16, 21 and 22.) The inner end of said arm is provided with two cam slots 283, 284, in which cams 285, 286, fixed to rotate with the cam sleeve 151, are rotatable. This cam sleeve extends across the machine so as to connect the cams at the respective sides of the printing press, in order to simultaneously move both ends of the form roller 113. It will be noted from Figs. 21 and 22 that said cam slots are arranged in crossing relation, and that the cams are arranged in substantial oppositely extending relation for obtaining the desired sequential movements of the arm 237.

The arm 247 is provided with a guideway 291 in which a guide block 292 is received, the guide block being rockable on the flanged sleeve 91. (See Figs. 6, 7, 16, 23 and 24.) The inner end of said arm is provided with two cam slots 293, 294, in which cams 295, 296, fixed to rotate with the cam sleeve 151, are rotatable. This cam sleeve extends across the machine so as to connect the cams at the respective sides of the printing press, in order to simultaneously move both ends of the form roller 111. It will be noted from Figs. 23 and 24 that said cam slots are arranged in crossing relation, and that the cams are arranged in substantial oppositely extending relation for obtaining the desired sequential movements of the arm 247.

The arm 257 is provided with a guideway 301 in which a guide block 302 is received, the guide block being rockable on the flanged sleeve 91. (See Figs. 6, 7, 16, 25 and 26.) The inner end of said arm is provided with two cam slots 303, 304, in which cams 305, 306, fixed to rotate with the cam sleeve 151, are rotatable. This cam sleeve extends across the machine so as to connect the cams

at the respective sides of the printing press, in order to simultaneously move both ends of the form roller 112. It will be noted from Figs. 25 and 26 that said cam slots are arranged in crossing relation, and that the cams are arranged in substantial oppositely extending relation for obtaining the desired sequential movements of the arm 257.

The construction and relation of parts for effecting the movements of the form rollers toward and away from the form cylinder and toward and away from the reciprocating rollers coacting therewith are illustrated in Figs. 19 to 26 inclusive.

Fig. 19 shows the adjustment of the lowermost form roller for normal printing relation.

Fig. 20 illustrates the relation of this form roller and the parts for effecting such relation, when the form roller is moved away from the form cylinder and also away from the lower reciprocating roller.

Fig. 21 illustrates the normal position of the intermediate lower form roller and the parts for controlling the position of the same, whereas Fig. 22 shows the positions of the intermediate lower form roller away from the form cylinder and its coacting reciprocating roller.

It will be noted from a comparison of Figs. 20 and 22 that the movements of the lowermost form roller and of the intermediate lower form roller are in opposite directions with relation to the reciprocating roller therebetween.

Fig. 23 shows the normal position of the uppermost form roller and its positioning parts, whereas Fig. 24 shows the free position of said form roller and the relations of the corresponding positioning parts.

Fig. 25 shows the normal position of the intermediate upper form roller and its positioning parts, and Fig. 26 shows the free position of said form roller and its positioning parts.

The movements of the form rollers are controlled by the hand wheel 145 on the shaft 130 hereinbefore described. (See Fig. 4.)

The cam sleeve 151 surrounds the shaft 150. This cam sleeve has a worm gear 311 fixed thereto. (See Figs. 4, 7 and 15.) A worm 312 is journaled in bearings 313, 314, of a plate 315 rotatable about and with said shaft. A pull-pin 316 is axially movable in a bore 317 in an extension 318 of the segment gear 149. A spring 319 normally urges said pull pin into a hole 320 in said plate, for connecting said plate with said segment gear, in order to cause the two to move together. The segment gear is rotated by the hand wheel 145 in manner hereinbefore described, (see Figs. 4, 5, 6 and 7), the rotation of this segment gear carrying the worm plate 315 with it, when said worm plate is connected with said segment gear by means

of said pull pin, thereby rotating the cam sleeve.

The sleeve 91 has the clamp block 321 thereabout in a bearing 322 of the bearing spider 32. (See Figs. 1, 2, 6 and 7.) The outer end of the sleeve is threaded and has a nut 323 thereon. The clamp block bears against the arm 257 (referring to the upper part of Fig. 7), which bears upon the arm 210, which in turn bears upon the arm 209, the latter bearing upon the arm 247, and the arm 247 bearing upon the flange of the sleeve 91, which is fixed to the frame. When the nut is in clamped position, all the parts are clamped together for being securely maintained in their adjusted positions. The nut is provided with an operating handle 324.

The sleeve 92 has a clamp block 331 thereabout in a bearing 332 of the bearing spider 32, (see Figs. 1, 2, 6 and 7). The outer end of the sleeve is threaded and has a nut 333 thereon. The clamp block bears against the arm 237 (referring to the lower part of Fig. 7), which bears upon the arm 211, which in turn bears upon the arm 212, the latter bearing upon the arm 227, and the arm 227 bearing upon the flange of the sleeve 92 which is fixed to the frame. When the nut is in clamped position all of the parts are clamped together for being securely maintained in their adjusted positions. The nut 333 is provided with an operating handle 334.

If now it is desired to adjust the relation of the arms individually, the corresponding clamp nuts are released for permitting such adjustment. If it is desired to adjust all of the form rollers simultaneously, the clamp nuts are relieved for relieving pressure upon the arms and permitting their movements with relation to each other.

If it is desired to move the form rollers and the distributing rollers so as to free the same from contact, the pull pin 316 is allowed to remain in its hole 320 so as to connect the worm plate 315 with the segment gear 149, so that not only the shaft 150 shall be rotated, but the cam sleeve 151 will be rotated therewith. Rotation of said shaft controls the position of the distributing rollers, and the rotation of said sleeve controls the positions of the form rollers.

If it is desired to move the form rollers out of contact only with the form cylinder, for distributing the ink evenly upon all of the inking rollers, the hand wheel 145 is turned so as to release contact between the form rollers and the form cylinder, whereupon the pull pin 316 is moved out of its hole 320 for disconnecting the shaft 150 from the cam sleeve 151, whereupon the hand wheel is reversely rotated, for again causing contact between the distributing rollers and the reciprocating roller coacting therewith, while the form rollers are allowed

to remain in uncontacted position with relation to the form cylinder.

The distributing rollers may, if desired, be moved away from their coacting reciprocating roller independent of movement of the form rollers, which is effected by releasing the pull pin 316 out of its hole 320 so as to disconnect the segment gear 149 from the worm plate 315, which enables the distributing rollers to be moved without movement of the form rollers. The distributing rollers may further be moved by means of the hand wheel either toward or from the reciprocating roller coacting therewith, regardless of the positions of the form rollers, merely by the disconnection of the pull pin. These handles 183, 324, 334, are in close relation to the hand wheel 145 so that quick manipulation of the rollers may be had.

20 The clamping means frictionally hold the moved parts so that creeping of the same during operation of the press is prevented. If desired, the clamping means may be so adjusted as to apply sufficient friction on the moved parts to prevent such creeping, while permitting such frictional holding to be overcome by the operation of the hand wheel 145. With this relation the unclamping of the clamping means is not required 25 at each operation of the hand wheel for moving the parts.

The composition rollers may be moved so as to be substantially spaced from the printing form and from the endwise reciprocating rollers and the feeding roller, in order that ready access may be had to all the inked surfaces of all the rollers for ready cleaning of the same, in which relation the composition rollers are readily turned by hand, and all the other rollers may also be readily turned without contact of their inking surfaces, so as to expose all parts of the rollers to the operator for ready cleaning.

The frame 31 may be movable on a base 45 335 toward and from the form cylinder on roller cages 336 and guided by lateral guides 337, by suitable mechanism, whereby the end of the inking mechanism nearest the form cylinder is made more accessible to the operator, who may reach into or move in the space between the inking mechanism and the form cylinder when the former is moved away from the latter.

The ready movement of the composition 55 rollers out of contact with the printing form and all coacting rollers also permits all the composition rollers to rest free of contact when the press is not being operated, to prevent the formation of flat spots or indentations in the same.

In the operation of the printing press it frequently occurs that the diameters of the composition rollers will vary. Thus the 60 diameters of the form rollers will increase during operation, due to the heat caused

during operation or due to the ink employed. I provide means whereby all of the form rollers may be simultaneously adjusted toward and away from the form cylinder, accomplished in the present exemplification, 70 by an adjustment of the cam sleeve 151 about its axis. The adjustment of this cam sleeve about its axis changes the positions of the cams thereon, and consequently of the arms controlled thereby, for such adjustment of 75 the form rollers. This adjustment of the cam sleeve is accomplished by the worm 312 and the worm segment 311 hereinbefore described. The shaft of the worm is preferably provided with a scale 339 with which 80 a pointer on the worm plate coacts for determination of fine adjustments. (See Fig. 15.)

The composition rollers are rotated by frictional contact with the reciprocating rollers. The reciprocating rollers are driven. The peripheral speeds of the rotating form rollers are equal to the peripheral speed of the rotating form surface on the form cylinder and the reciprocating rollers coacting therewith.

A drive shaft 341 may be rotated from any suitable part of the printing press. A bevel gear 342 is fixed to this drive shaft, the hub of the same being journaled in a bearing 343 90 on a bracket 344 extending from the frame. (See Figs. 1 and 9.)

A bevel gear 345 meshes with the bevel gear 342, on a shaft 346 journaled in a bearing 347 in said bracket and a bearing 348 on the bracket 44, (see Fig. 9). This shaft carries a pinion 348 thereon, which meshes with gear 350, which is fixed to the axle of the large reciprocating roller 71. The gear 350 meshes with pinions 351, 352. (See Figs. 100 8 and 9.) These pinions mesh with gears 353, 354, fixed to the axles 89, 90, of the smaller reciprocating rollers 87, 88. The pinions 351, 352, are respectively journaled 105 on bearings 355 on stud shafts 356 fixed in the frame.

Having thus fully described my invention, what I claim as new, and desire to secure by Letters Patent, is:

1. In inking mechanism for a printing press, the combination with the printing form, of form rollers, coacting rollers, means whereby to move said form rollers about the outer peripheries of said coacting rollers with which said form rollers have contact for distance relation of said form rollers with said printing form, and means for moving said form rollers for distance relation with said coacting rollers, said two named means operative for effecting said two movements in sequence.

2. In inking mechanism for a printing press, the combination of a printing form, composition form rollers, composition distributing rollers, coacting rollers for said

composition rollers, and connected means having operative connections with said composition rollers moving said composition rollers respectively for distance relation with 5 said printing form and with said coacting rollers, said connected means including a releasable connection for movement of only a portion of said composition rollers.

3. In inking mechanism for a printing 10 press, the combination of an endwise reciprocating inking roller of greater diameter, sets of composition distributing rollers at the respective sides thereof, endwise reciprocating inking rollers of smaller diameter 15 with which outer ones of said sets of distributing rollers respectively coact for transferring ink thereto, sets of pairs of composition form rollers coacting with said last-named reciprocating rollers; means for moving 20 said form rollers about the outer peripheries of said last-named reciprocating rollers and for distance relation with the same, and means for moving said distributing rollers for distance relation with all said reciprocating rollers, whereby to free said composition rollers from contact with said reciprocating rollers.

4. In inking mechanism for a printing 30 press, the combination with a printing form, of composition form rollers, endwise reciprocating inking rollers coacting therewith, composition distributing rollers, an endwise reciprocating roller, said composition distributing rollers coacting with all said endwise reciprocating rollers, and means for moving said composition form rollers about said first-named reciprocating inking rollers for distance relation with said printing form and laterally for distance relation with said 35 first-named reciprocating rollers, in sequence, and means for moving said composition distributing rollers for distance relation with said second-named reciprocating roller, whereby to free said composition rollers 40 from said printing form and from said reciprocating rollers.

5. In inking mechanism for a printing 50 press, the combination with a printing form, of composition form rollers, endwise reciprocating inking rollers coacting therewith, composition distributing rollers, an endwise reciprocating roller, said composition distributing rollers coacting with all said endwise reciprocating rollers, and means for moving said composition form rollers about said first-named reciprocating inking rollers for distance relation with said printing form and laterally for distance relation with said first-named reciprocating rollers, in sequence, means for moving said composition distributing rollers for distance relation with said second-named reciprocating roller, whereby to free said composition rollers from 55 said printing form and from said reciprocating rollers, and releasable connecting means 60 65

connecting said last two named means for combined movements, and constructed and arranged whereby upon release of said connecting means said distributing rollers may be independently moved. 70

6. In inking mechanism for a printing press, the combination of an inking roller, sets of inking rollers thereabout, a plurality of inking rollers, pairs of inking rollers coacting therewith, means for moving the inking rollers of said respective pairs of inking rollers toward and from said plurality of inking rollers, means for moving said sets of inking rollers toward and from said first-named inking roller, said means connected for combined movements, and releasable connecting means between said last two named means. 75

7. In inking mechanism for a printing 80 press, the combination of an inking roller, sets of distributing rollers thereabout, a plurality of inking rollers receiving ink from the latter, form rollers coacting with said plurality of inking rollers, means for moving said form rollers about the axes of said plurality of inking rollers toward and from a printing form, and means for moving said form rollers toward and from said plurality of inking rollers, said last two named means connected for sequential movements of said form rollers in said last two named directions. 85

8. In inking mechanism for a printing 90 press, the combination of an inking roller, sets of distributing rollers thereabout, a plurality of inking rollers receiving ink from the latter, form rollers coacting with said plurality of inking rollers, means for moving said form rollers about the axes of said plurality of inking rollers toward and from a printing form, means for moving said form rollers toward and from said plurality of inking rollers, said last two named means connected for sequential movements of said form rollers in said last two named directions, means for moving said distributing rollers toward and from said first-named roller, said last two named means arranged for combined movements, and a single operating part for moving said three named means. 95

9. In inking mechanism for a printing 100 press, the combination of an inking roller, sets of distributing rollers thereabout, a plurality of inking rollers receiving ink from the latter, form rollers coacting with said plurality of inking rollers, means for moving said form rollers about the axes of said plurality of inking rollers toward and from a printing form, means for moving said form rollers toward and from said plurality of inking rollers, said last two named means connected for sequential movements of said form rollers in said last two named directions, means for moving said distributing 105

110

115

120

125

130

rollers toward and from said first-named roller, said last two named means arranged for combined movements, a single operating part for moving said three named means, 5 and clamping means for said three named means.

10. In inking mechanism for a printing press, the combination of an inking roller, sets of distributing rollers thereabout, a plurality of inking rollers receiving ink from the latter, form rollers coacting with said plurality of inking rollers, means for moving said form rollers about the axes of said plurality of inking rollers toward and from 15 a printing form, means for moving said form rollers toward and from said plurality of inking rollers, said last two named means connected for sequential movements of said form rollers in said last two named 20 directions, means for moving said distributing rollers toward and from said first-named roller, said last two named means arranged for combined movements, friction clamping means for holding said three named means 25 in moved relations against creeping during operation of the press, and operating means for moving said three named means overcoming the friction resistance of said friction clamping means.

30 11. In inking mechanism for a printing press, the combination of an endwise reciprocating inking roller, sets of distributing rollers thereabout, a pair of endwise reciprocating inking rollers, rollers of said sets of 35 distributing rollers coacting with the latter, a pair of form rollers coacting with each of said last-named endwise reciprocating rollers, means moving said form rollers of said respective pairs of form rollers in opposite directions about the peripheries of their 40 respective reciprocating rollers toward and from the printing form, means for moving said form rollers toward and from said last-named reciprocating rollers sequentially 45 with relation to said last-named means, means for moving said sets of distributing rollers toward and from said first-named reciprocating roller, and releasable connecting means connecting said last two named 50 means.

55 12. In inking mechanism for a printing press, the combination of an endwise reciprocating inking roller, sets of distributing rollers thereabout, a pair of endwise reciprocating inking rollers, rollers of said sets of distributing rollers coacting with the latter, a pair of form rollers coacting with each of said last-named endwise reciprocating rollers, means moving said form rollers 60 of said respective pairs of form rollers in opposite directions about the peripheries of their respective reciprocating rollers toward and from the printing form, means for moving said form rollers toward and from said last-named reciprocating rollers sequentially 65

with relation to said last-named means, means for moving said sets of distributing rollers toward and from said first-named reciprocating roller, releasable connecting means connecting said last two named 70 means, and adjusting means for combinedly adjusting said form rollers about the peripheries of their respective reciprocating rollers toward and from the printing form whereby to compensate for variations in diameters of said form rollers during printing. 75

13. In inking mechanism for a printing press, the combination of form rollers, distributing rollers, endwise reciprocating inking rollers respectively for said form rollers and for said distributing rollers, means for combinedly moving said form rollers, means for combinedly moving said distributing rollers, releasable connecting means between 80 said last two named means, and adjusting means at the latter for combinedly adjusting the contact relation between said form rollers and the printing form. 85

14. In inking mechanism for a printing press, the combination of form rollers, a coacting inking roller therefor, distributing rollers, a coacting inking roller therefor, pivot means and slide means between said form rollers and said first-named coacting 90 inking roller, slide means between said distributing rollers and said second-named coacting inking roller, and a single operating element moving said form rollers on said pivot means and said form rollers and 95 said distributing rollers on said respective slide means. 100

15. In inking mechanism for a printing press, the combination of form rollers, a coacting inking roller therefor, distributing 105 rollers, a coacting inking roller therefor, pivot means and slide means between said form rollers and said first-named coacting inking roller, shifting means whereby to move said form rollers on said pivot means and on said slide means in sequence, slide means between said distributing rollers and said second-named coacting inking roller, shifting means whereby to move said distributing rollers on said last-named slide 110 means, and a single operating element having operative connections with said two named shifting means. 115

16. In inking mechanism for a printing press, the combination of form rollers, a coacting inking roller therefor, distributing rollers, a coacting inking roller therefor, pivot means and slide means between said form rollers and said first-named coacting 120 inking roller, shifting means whereby to move said form rollers on said pivot means and on said slide means in sequence, slide means between said distributing rollers and said second-named coacting inking roller, shifting means whereby to move said 125 130

- tributing rollers on said last-named slide means, releasable connecting means between said two named shifting means, and a single operating element having operative connections with said two named shifting means.
17. In inking mechanism for a printing press, the combination of form rollers, a coacting inking roller therefor, distributing rollers, a coacting inking roller therefor, pivot means and slide means between said form rollers and said first-named coacting inking roller, shifting means whereby to move said form rollers on said pivot means and on said slide means in sequence, means whereby to simultaneously adjust said form rollers in opposite directions about said pivot means, slide means between said distributing rollers and said second-named coacting inking roller, shifting means whereby to move said distributing rollers on said last-named slide means, and a single operating element having operative connections with said two named shifting means.
18. In inking mechanism for a printing press, the combination of form rollers, a coacting inking roller therefor, distributing rollers, a coacting inking roller therefor, pivot means and slide means between said form rollers and said first-named coacting inking roller, shifting means whereby to move said form rollers on said pivot means and on said slide means in sequence, slide means between said distributing rollers and said second-named coacting inking roller, shifting means whereby to move said distributing rollers on said last-named slide means, a single operating element having operative connections with said two named shifting means, and clamping means whereby to clamp said shifting means in moved positions.
19. In inking mechanism for a printing press, the combination of an endwise reciprocating inking roller, distributing rollers thereabout, movable supporting means for the latter at each side of the printing press, cam means at each side of the printing press for moving the same, a cross-shaft, gearing at each side of the printing press between said cam means and said cross-shaft, a cam sleeve about said cross-shaft, cams thereon at each side of the printing press, additional endwise reciprocating inking rollers, form rollers coacting with the latter, movable supporting means at each side of the printing press for the latter, pivot means and cam means at each side of the printing press for said last-named movable supporting means, said last-named movable supporting means provided with coacting means for said last-named cams, a single operating element for said cross-shaft and said cam sleeve, and adjusting means whereby to adjust the operative relation between said cross-shaft and said cam sleeve.
20. In inking mechanism for a printing press, the combination of an endwise reciprocating inking roller, distributing rollers

thereabout, movable supporting means for the latter at each side of the printing press, cam means at each side of the printing press for moving the same, a cross-shaft, gearing at each side of the printing press between said cam means and said cross-shaft, a cam sleeve about said cross-shaft, cams thereon at each side of the printing press, additional endwise reciprocating inking rollers, form rollers coacting with the latter, movable supporting means at each side of the printing press for the latter, pivot means and cam means at each side of the printing press for said last-named movable supporting means, said last-named movable supporting means provided with coacting means for said last-named cams, a single operating element for said cross-shaft and said cam sleeve, and releasable connecting means between said cross-shaft and said cam sleeve.

21. In inking mechanism for a printing press, the combination of an endwise reciprocating inking roller, distributing rollers thereabout, movable supporting means for the latter at each side of the printing press, cam means at each side of the printing press for moving the same, a cross-shaft, gearing at each side of the printing press between said cam means and said cross-shaft, a cam sleeve about said cross-shaft, cams thereon at each side of the printing press, additional endwise reciprocating inking rollers, form rollers coacting with the latter, movable supporting means at each side of the printing press for the latter, pivot means and cam means at each side of the printing press for said last-named movable supporting means, said last-named movable supporting means provided with coacting means for said last-named cams, a single operating element for said cross-shaft and said cam sleeve, and adjusting means whereby to adjust the operative relation between said cross-shaft and said cam sleeve.

22. In inking mechanism for a printing press, the combination of an inking roller, a second inking roller coacting with the latter, a supporting part for said second inking roller, a loop for the latter about the axis of rotation of said first-named inking roller, and cam means about said axis coacting with said loop for adjusting said supporting part.

23. In inking mechanism for a printing press, the combination of an inking roller, opposed inking rollers coacting with the latter, said first-named inking roller between said opposed inking rollers, supporting parts for said respective opposed inking rollers, a loop for each of the latter about the axis of rotation of said first-named inking roller, and cam means about said axis acting on said supporting parts whereby to adjust said supporting parts about said axis.

24. In inking mechanism for a printing press, the combination of an inking roller,

• a second inking roller coacting therewith, a supporting part, a guide thereon, a slide thereon for said second-named inking roller, and screw-operated cam means between said 5 slide and said supporting part for adjusting the distance between said slide and said first-named inking roller.

25. In inking mechanism for a printing press, the combination of an inking roller, 10 a second inking roller coacting therewith, and means for adjusting said second inking roller with relation to said first-named inking roller comprising a base, a support, guiding means between said support 15 and said base guiding said support on an arc substantially about the outer periphery of said first-named inking roller, a slide on said support extending in a direction crosswise of said arc, a bearing thereon for said second-named inking roller, adjusting means between said base and said support, and adjusting means between said slide and said support.

26. In inking mechanism for a printing 25 press, the combination of an inking roller, a second inking roller coacting therewith, and means for adjusting said second inking roller with relation to said first-named inking roller comprising a base, a support, guiding means between said support and said base guiding said support on an arc substantially about the outer periphery of said first-named inking roller, a slide on said support extending in a direction crosswise of said arc, a bearing thereon for said second-named inking roller, adjusting means between said base and said support, and adjusting means between said slide and said support, said adjusting means including endwise adjustable cam means having cam movements at substantial angles with relation to each other.

27. In inking mechanism for a printing 45 press, the combination of an inking roller, a second inking roller coacting therewith, and means for adjusting said second inking roller with relation to said first-named inking roller comprising a base, a support, guiding means between said support and said base guiding said support on an arc substantially about the outer periphery of said first-named inking roller, a slide on said support extending in a direction crosswise of said arc, a bearing thereon for said second-named inking roller, an axially adjustable screw-operated cam means for adjusting said support on said base, and an axially adjustable screw-operated cam means for adjusting said slide on said support.

28. In inking mechanism for a printing 60 press, the combination of an inking roller, a second inking roller coacting therewith, and means for adjusting said second inking roller with relation to said first-named inking roller comprising a base, a support, guid-

ing means between said support and said base guiding said support on an arc substantially about the outer periphery of said first-named inking roller, said support provided with a guideway in a plane extending crosswise of said arc, a slide on said guideway, a bearing thereon for said second-named inking roller, a screw-controlled cam block and groove adjustment between said slide and said support extending in a plane substantially parallel to said guideway, and a screw-controlled cam block and groove adjustment between said support and said base extending in a plane at a substantial angle to said last-named plane.

29. In inking mechanism for a printing 70 press, the combination of an inking roller, a second inking roller coacting therewith, and means for adjusting the latter with relation to the former comprising a pair of members, one of said members provided with an oblique slot slanting in the direction of adjustment, a cam block guided thereby, and a screw rod having threaded connection with said cam block, said screw rod held endwise with relation to said members, whereby rotation of said screw rod moves said cam block axially for lateral adjustment between said members.

30. In inking mechanism for a printing 75 press, the combination of an inking roller, a second inking roller coacting therewith, a base, a support, said base and said support constituting a pair of members, means for guiding said support on an arc substantially 80 concentric with the outer periphery of said first-named inking roller, a slide, said support and said slide constituting a pair of members, means for guiding said slide crosswise of said arc, a member of each of said 85 pair of members provided with an oblique slot, a cam block guided thereby, and a screw rod having threaded connection with said cam block, said screw rod held endwise with relation to said members, and said respective slots and cam blocks slanting in crossing relation, whereby 90 rotations of said respective screw rods move said respective cam blocks axially for relative adjustments in different directions of 95 said support and said slide.

31. In inking mechanism for a printing 100 press, the combination with a ductor roller and disturbing rollers, of a feeding roller between said ductor roller and said distributing rollers, a shaft therefor, and means for adjusting said feeding roller for parallel relation with said other rollers comprising a bearing for said shaft, a slide for said bearing, a support, a guideway on the latter for said slide, a second slide, means for adjusting said last-named slide edgewise on 105 said support, said first-named slide and said support provided with registering holes, and a connecting stem extending through said 110

115 120 125 130

holes, said connecting stem having connections respectively with said bearing and said second-named slide, and means clamping said support between said bearing and said second-named slide.

32. In inking mechanism for a printing press, the combination with a ductor roller and distributing rollers, of a feeding roller between said ductor roller and said distributing rollers, a shaft therefor, and means for adjusting said feeding roller for parallel relation with said other rollers comprising a bearing for said shaft, a slide for said bearing, a support, a guideway on one side of the latter for said slide, a plate on the other side of said support, spaced apart bearings on said plate, a bolt journaled in said bearings and held endwise therein, a second slide between said last-named bearings threaded to said bolt, registering holes in said guideway, said plate and said support, and a second bolt in said holes journaled in said second-named slide and having threaded connection with said first-named slide for simultaneous adjustments of said slides and holding said slides in adjusted positions.

33. In inking mechanism for a printing press, the combination of a central inking roller, distributing rollers thereabout, and means for adjusting said distributing rollers comprising a base, a support, guiding means between said base and said support, extending in radial direction with relation to said central inking roller, adjusting means between the same, a slide, arcuate guiding means between said slide and said support, adjusting means between the same, and a second slide comprising bearing means for a distributing roller, guiding means between said slides extending in a direction crosswise of said arcuate guiding means, and adjusting means between the same.

34. In inking mechanism for a printing press, the combination of a central inking roller, distributing rollers thereabout, and means for adjusting said distributing rollers comprising a base, a support, guiding means between said support and said base, a guide on said support, a rocker cam, a shoe between said cam and said guide and coacting with both, and bearing means for a distributing roller supported by said support, and constructed and arranged for adjusting the distance relation between said distributing roller and said first-named inking roller.

35. In inking mechanism for a printing press, the combination of a central inking roller, distributing rollers thereabout, and means for adjusting said distributing rollers comprising a base, a support, guiding means between said support and said base, a guide on said support, a rocker cam, a shoe between said cam and said guide and coacting with both, a slide, an arcuate guide between

said slide and said support substantially concentric with said first-named roller, means for adjusting said slide on said arcuate guide, and bearing means for a distributing roller supported by said slide.

36. In inking mechanism for a printing press, the combination of a central inking roller, distributing rollers thereabout, and means for adjusting said distributing rollers comprising a base, a support, guiding means between said support and said base, a guide on said support, a rocker cam, a shoe between said cam and said guide and coacting with both, bearing means for a distributing roller supported by said support, and constructed and arranged for adjusting the distance relation between said distributing roller and said first-named inking roller, and means for clamping said base, said support and said slide in adjusted positions.

37. In inking mechanism for a printing press, the combination of a central inking roller, distributing rollers thereabout, and means for adjusting said distributing rollers comprising a base, a support, guiding means between said support and said base, a guide on said support, a rocker cam, a shoe between said cam and said guide and coacting with both, a slide, an arcuate guide between said slide and said support substantially concentric with said first-named roller, means for adjusting said slide on said arcuate guide, a second slide, a guide crosswise of said arcuate guide, means for adjusting said second-named slide on said second-named guide, and bearing means for a distributing roller on said second-named slide.

38. In inking mechanism for a printing press, the combination of a central inking roller, sets of distributing rollers at the respective sides of said inking roller, a base, a support for each of said sets of distributing rollers, means for guiding said respective supports in directions transverse to the outer periphery of said central inking roller, a plurality of slides for each of said sets of distributing rollers, bearings thereon for said distributing rollers, arcuate guiding means substantially concentric with said periphery, said arcuate guiding means located between said slides and said supports, and means independently adjusting said slides on said arcuate guiding means for lateral adjustments of said distributing rollers about said central inking roller.

39. In inking mechanism for a printing press, the combination of a central inking roller, sets of distributing rollers at the respective sides of said inking roller, a base, a support for each of said sets of distributing rollers, means for guiding said respective supports in directions transverse to the outer periphery of said central inking roller, a plurality of slides for each of said sets of distributing rollers, bearings thereon for

said distributing rollers, arcuate guiding means substantially concentric with said periphery, said arcuate guiding means located between said slides and said supports, means independently adjusting said slides on said arcuate guiding means for lateral adjustments of said distributing rollers about said central inking roller, and clamping means about the axis of rotation of said central inking roller for simultaneously clamping said base, said supports and said slides in adjusted positions.

40. In inking mechanism for a printing press, the combination of a central inking roller, sets of distributing rollers at the respective sides of said inking roller, a base, a support for each of said sets of distributing rollers, means for guiding said respective supports in directions transverse to the outer periphery of said central inking roller, oppositely extending cams about the axis of rotation of said central inking roller, said supports extending to opposite sides of said axis, guides on said respective supports on said opposite sides, and shoes for each of said supports at the respective sides of said axis between said cams and said guides and co-acting with both said cams and said guides.

41. In inking mechanism for a printing press, the combination of a central inking roller, sets of distributing rollers at the respective sides of said inking roller, a base, a support for each of said sets of distributing rollers, means for guiding said respective supports in directions transverse to the outer periphery of said central inking roller, oppositely extending cams about the axis of rotation of said central inking roller, said supports extending to opposite sides of said axis, guides on said respective supports on said opposite sides, shoes for each of said supports at the respective sides of said axis between said cams and said guides and coacting with both said cams and said guides, a plurality of slides on each of said supports, arcuate guides between said slides and said supports, said arcuate guides substantially concentric with the outer periphery of said central inking roller, and means for adjusting said slides on said respective supports for adjusting the distance relation between said slides.

42. In inking mechanism for a printing press, the combination of a central inking roller, sets of distributing rollers at the opposite sides of said central inking roller, a base, a support for each of said sets of distributing rollers, means for guiding said respective supports in directions transverse to the outer periphery of said central inking roller, said supports provided with oppositely extending loops about the axis of rotation of said central inking roller, parallel guides respectively on said supports and said loops, oppositely presented shoes slidable thereon, and oppositely extending cams respectively co-operating with the oppositely presented shoes of said respective supports.

43. In inking mechanism for a printing press, the combination of a central inking roller, sets of distributing rollers at opposite sides of said central inking roller, a base, a support for each of said sets of distributing rollers, means for guiding said respective supports in directions transverse to the outer periphery of said central inking roller, said supports provided with oppositely extending loops about the axis of rotation of said central inking roller, parallel guides respectively on said supports and said loops, oppositely presented shoes slidable thereon, oppositely extending cams respectively co-operating with the oppositely presented shoes of said respective supports, and means for clamping said supports to said base.

44. In inking mechanism for a printing press, the combination of a central inking roller, a base, supports at opposite sides of the axis of rotation of said roller, a set of relatively laterally arranged distributing rollers for each of said supports, said distributing rollers coacting with said central inking roller, inking rollers coacting with said respective sets of distributing rollers at the respective ends of said sets, guides between said supports and said base which are substantially radial with relation to said central inking roller and substantially parallel with radial lines located about midway in the angles between the axes of said co-acting inking rollers and said central inking roller, cams about the axis of rotation of said central inking roller, and means operatively connecting said supports and cams.

45. In inking mechanism for a printing press, the combination of a central inking roller, a base, supports at opposite sides of the axis of rotation of said roller, a set of relatively laterally arranged distributing rollers for each of said supports, said distributing rollers coacting with said central inking roller, inking rollers coacting with said respective sets of distributing rollers at the respective ends of said sets, guides between said supports and said base which are substantially radial with relation to said central inking roller and substantially parallel with radial lines located about midway in the angles between the axes of said coacting inking rollers and said central inking roller, cams about the axis of rotation of said central inking roller, and means operatively connecting said supports and cams.

46. In inking mechanism for a printing press, the combination of a central inking roller, sets of distributing rollers at the opposite sides of said central inking roller, a base, a support for each of said sets of distributing rollers, means for guiding said respective supports in directions transverse to the outer periphery of said central inking roller, said supports provided with oppositely extending loops about the axis of rotation of said central inking roller, parallel guides respectively on said supports and said loops, oppositely presented shoes slidable thereon, and means for laterally adjusting said slides.

on said arcuate guides for contact relation between said outside distributing rollers and said respective coating inking rollers.

46. In inking mechanism for a printing press, the combination of a form inking roller, an inking roller coacting therewith, a pair of arms having bearing connection about the axis of rotation of said second-named inking roller, said form inking roller journaled on one of said arms, means for adjusting said last-named arm about the axis of said bearing connection, and means for moving the axis of said bearing connection crosswise with relation to said first-named axis.

47. In inking mechanism for a printing press, the combination of a form inking roller, an inking roller coacting therewith, a pair of arms having bearing connection about the axis of rotation of said second-named inking roller, a slide on one of said arms, bearing means on the latter for said form roller, means for adjusting the distance between said slide and said second-named inking roller, means for adjusting said last-named arm about the axis of said bearing connection, and means for moving said arms about and crosswise with relation to said first-named axis.

48. In inking mechanism for a printing press, the combination of a form inking roller, an inking roller coacting therewith, a pair of arms having bearing connection about the axis of rotation of said second-named inking roller, a slide on one of said arms, bearing means on the latter for said form roller, means for adjusting the distance between said slide and said second-named inking roller, means for adjusting said last-named arm about the axis of said bearing connection, and connected cam means having operative connections with the other of said arms moving said arms in sequence about and crosswise with relation to said first-named axis.

49. In inking mechanism for a printing press, the combination of a form inking roller, an inking roller coacting therewith, a pair of arms having bearing connection about the axis of rotation of said second-named inking roller, said form inking roller journaled on one of said arms, a slide block pivoted about said axis, said arms having slide connection with said slide block, and connected cam means having operative connections with the other of said arms moving said arms in sequence on said slide block as a pivot and on said slide block lengthwise of said slide connection.

50. In inking mechanism for a printing press, the combination of a form inking roller, an inking roller coacting therewith, a pair of arms having bearing connection about the axis of rotation of said second-

named inking roller, said form inking roller journaled on one of said arms, a slide block pivoted about said axis, said arms having slide connection with said slide block, the other of said arms provided with crossing cam slots, and relatively angularly arranged cams cooperating with said respective cam slots for moving said arms on said slide block as a pivot and on said slide block lengthwise of said slide connection.

51. In inking mechanism for a printing press, the combination of an inking roller, a pair of form inking rollers coacting therewith, a pair of arms for each of said form inking rollers, each of said pair of arms having bearing connection about the axis of rotation of said first-named inking roller, bearing means on an arm of each of said pair of arms for said respective form rollers, a slide block for each of said pair of arms pivoted about said axis, and connected cam means having operative connections with the other of said arms of each of said pair of arms moving said arms of each of said pair of arms in opposite directions in sequence on said slide blocks as pivots and crosswise of said slide blocks.

52. In inking mechanism for a printing press, the combination of a plurality of sets of pairs of form rollers, an inking roller between the form rollers of each of said pairs coacting with said form rollers, a supporting arm for each of said form rollers, means whereby the arms for each of said pairs of form rollers have pivotal movement and sliding movement about the axis of said coacting inking roller, and cam means acting on all said arms causing said pivotal movement and said sliding movement.

53. In inking mechanism for a printing press, the combination of a plurality of sets of pairs of form rollers, an inking roller between the form rollers of each of said pairs coacting with said form rollers of each pairs coacting with said form rollers, a supporting arm for each of said form rollers, means whereby the arms of each of said pairs of form rollers have pivotal movement and sliding movement about the axis of said coacting inking roller, each of said arms provided with crossing cam slots, and cams co-operating with said slots causing pivotal movement and sliding movement in sequence of said arms about said axes.

54. In inking mechanism for a printing press, the combination of a plurality of sets of pairs of form rollers, an inking roller between the form rollers of each of said pairs coacting with said form rollers, a supporting arm forming pairs of arms for said respective pairs of form rollers, pivot means and slide means for each of said pair of arms about the axis of said coacting ink-

ing roller, a secondary arm for each of said arms, a bearing on each of the latter for said respective form rollers, means for adjusting said secondary arms with relation to said first-named arms respectively for adjusting the relation between said form rollers and said coating inking rollers, each of said first-named arms provided with cam slots, and connected cams co-operating with said slots causing pivotal movements and sliding movements of said first named arms on said pivot means and said slide means.

In testimony whereof, I have hereunto signed my name.

LESLIE W. CLAYBOURN.
